BABY SLIPPER

Doris M. Ballinger and Charles R. Ballinger,
Sacramento, Calif.

Application March 16, 1954, Serial No. 29,562

Term of patent 14 years

(Cl. D7—7)

To all whom it may concern:

Be it known that we, Doris M. Ballinger and Charles R. Ballinger, have invented a new, original, and ornamental Design for a Baby Slipper, of which the following is a specification, reference being had to the accompanying drawing, forming a part hereof.

We claim:

The ornamental design for a baby slipper, as shown.
